COMBINED ELECTRICAL INDUCTION HEATING TABLE TOP COOKING RANGE AND OVEN

Philip H. Peters, Jr., Washington County, and John L. Matrone, Albany County, N.Y., assignors to Environment/One Corporation, Schenectady, N.Y.

Filed Sept. 23, 1971, Ser. No. 183,289

Term of patent 14 years

Int. Cl. D7—02; D6—04

U.S. Cl. D7—111

FIG. 2

FIG. 3

FIG. 1 is a front perspective view of a combined electrical induction heating table top cooking range and oven showing my new design;

FIG. 2 is a top plan view thereof;

FIG. 3 is a front elevation view thereof;

FIG. 4 is a rear elevation view thereof;

FIG. 5 is an end elevation view thereof as seen from the right of FIG. 1; and

FIG. 6 is an end elevation view thereof as seen from the left of FIG. 1.

We claim:

The ornamental design for combined electrical induction heating table top cooking range and oven, as shown.
